INVENTOR
VERNON J. DAVIS

BY

Popp and Powers
ATTORNEY

UNITED STATES PATENT OFFICE

VERNON J. DAVIS, OF BUFFALO, NEW YORK

RIDDLE

Application filed April 8, 1927. Serial No. 182,000.

This invention relates to improvements in riddles, proposing a construction which is especially intended for, altho not necessarily limited to, use in foundries for screening molding sand and embodies a mechanically operated screen adapted for arrangement under the hopper from which the sand is discharged and over the chain of molds whereby the sand is screened as it issues from the hopper.

One object of the invention is to provide a combination and arrangement of parts characterized by the location of the screen operating and supporting mechanism wholly beyond one end of the screen, the elimination of all overhead and base supports, and adequate provision for taking the weight of the screen box and the sand therein from the operating shaft.

A further object is to provide operating mechanism by which the screen has a path, speed and manner of vibrations such that it tends to break up most of the lumps in the sand and thus enables the effective use of a maximum quantity of sand.

A still further object is to provide for an arrangement of the screen box whereby it may be quickly and easily inverted for the purpose of discharging the accumulation on the screening fabric whenever such an accumulation has reached a point where it is desirable that the fabric be cleaned.

An embodiment of the invention is illustrated in the accompany drawings in which:

Figure 1 is a plan view.

Figure 2 is a side elevation.

Figure 3 is an enlarged side elevation of the motor and the supporting elements for the screen box.

Figure 4 is a partial front elevation of the motor and the supporting elements for the screen box, said elements being shown partly in vertical central section.

The screen box (not shown) is supported in a suitable horizontal frame 1 having a thumbscrew 2 by which said box is secured and the operating mechanism is located wholly beyond one end of this frame and is so constructed that it imposes substantially no weight load upon the operating

shaft. The riddle as an entirety is mounted on a suitable support from which it extends laterally. This support is preferably a swinging support which comprises a fixed bracket 3, a swinging bracket 4 and a pivot pin 5 whereby the riddle may be swung to one side when its use is not required. The swinging bracket 4 includes a verticle supporting plate 6 to which there is secured by bolts 7 the base 8 of an electric motor 9. The shaft 10 of the motor 9 vibrates an element by which the frame 1 is directly supported, said element preferably being in the form of a U-shaped hanger 14 having vertical arms 13 and a bridge piece 15 attached to the arms by bolts 16. Said shaft preferably carries at each end an operating eccentric 11 and these cooperate with eccentric straps 12 provided on the arms 13. The bridge piece 15 is formed with a longitudinal sleeve 17 for the support of a stem 18 by which the frame 1 is carried, said frame having a collar 19 in which said stem is fitted and secured by a pin 20. The eccentric straps 12 are shown in detail in Figure 4 and are each composed of rings secured together by bolts 21, the rings being formed to delimit an internal chamber for a suitable ball bearing 22 and also being provided with suitable packing 23.

The hanger 14 is acted on by suitable equalizing springs 24. The arms 13 are provided with rearward extensions 25 which carry a transverse bar 26 arranged behind the plate 6 and to which the springs 24 are connected, said springs at their remote ends being connected to the top and bottom lugs of the bracket 4, preferably by adjusting eyes 27. The bracket 4 includes at its sides vertical reenforcing flanges 28 and these are provided with enlarged circular openings 29 through which the bar 26 extends, the diameter of these openings permitting movements of the bar in all directions incident to the vibration of the hangers 13. The bracket 4 is provided at its upper end with a forwardly projecting arm 30 and a supporting spring 31 has its upper end connected to an eye 32 carried by the arm 30 and its lower end connected to an eye 33 attached to a forward

extension 34 of the sleeve 17, the spring 31, aided by the springs 24 serving to take the weight of the parts from the eccentrics 11 and thus minimize wear. The principal function of the springs 24 as equalizing springs is to hold the hanger 14 within a normal range of angles during its vibrations by the motor shaft. In this function the springs limit the vertical movements of the bar 26 without substantially limiting its horizontal movements whereby the frame 1 is progressively canted in fore and aft directions during its opposite vertical vibrations. The path in which the frame 1 vibrates is substantially elliptical. The vertical movements of the frame in its path of vibration are more rapid than the fall of the sand. Consequently the screening fabric will strike the sand with such force as to tend to break the lumps and cause them to rebound, this action being aided by the canting of the frame as described. The canting action of the frame also aids in promoting the fore and aft shifting of the mass of sand relatively to the screening fabric so as to secure rapid and most effective screening results.

The stem 18 is mounted whereby it may be turned in the sleeve 17, but is suitably held against accidental turning movement. Thus the stem has direct bearing in a suitable bushing 35 which is fitted within the sleeve but is sufficiently short to provide a chamber for an expansion spring 36 bearing at its ends against said bushing and against a head 37 at the rear end of the stem. The sleeve extension 34 is formed in its edge face with a notch 38 and the collar 19 is formed with a projection 39 which under the pressure of the spring 36 is caused normally to engage in the notch, the latter and the projection preferably being cam faced. When it is desired to clean the screening fabric the frame 1, which is secured to the stem 18 by the pin 20, is turned upside down with reference to said stem as an axis for the purpose of dislodging from the screening fabric the accumulated matter. In this turning movement the projection 39 rides along the inclined face of the notch and moves the stem axially against the pressure of the spring 36. When the accumulated matter has been discharged the frame 1 is restored to its original position in which it is held by the engagement of the projection 39 in the notch 38.

It will be observed that frame 1 is operated and entirely supported by mechanism which is located wholly beyond one end thereof and that the space above and below said frame is entirely unobstructed while at the same time the operating and supporting mechanism is such that no overhead or ground-attached supporting parts are required. In view of these characteristics the frame 1 may be instantly moved to a

position between the hopper and the chain of molds without any interference with said hopper or molds and in such position rapidly vibrated for the purpose of screening the sand as it is delivered from the hopper and in the course of its passage to the molds.

Having fully described my invention, I claim:

1. In a riddle the combination with a screen bearing frame of operating and supporting mechanism located wholly beyond one end thereof and including an element supporting said frame and connected to one end thereof, a motor, means operatively connecting the shaft of the motor and said element to vibrate the latter in an elliptic path and means for causing the frame to cant fore and aft at periods of its vibration.

2. In a riddle the combination with a screen bearing frame of operating and supporting mechanism located wholly beyond one end thereof and including a motor, a hanger pendant from the motor shaft and connected to one end of said frame, and eccentric and strap connections between said shaft and the hanger to vibrate the latter.

3. In a riddle the combination with a screen bearing frame of operating and supporting mechanism located wholly beyond one end thereof and including a motor, an element supporting said frame and connected to one end thereof, means operatively connecting the shaft of said motor and said element to vibrate the latter, and equalizing means for determining the angular positions of said element during its vibrations.

4. In a riddle the combination with a screen bearing frame of operating and supporting mechanism located wholly beyond one end thereof and including a motor, a hanger pendant from the motor shaft and connected to one end of said frame, eccentric and strap connections between said shaft and the hanger to vibrate the latter, and equalizing springs acting on said hanger for determining its angular positions during its vibrations.

5. In a riddle the combination with a screen bearing frame of operating and supporting mechanism located wholly beyond one end thereof and including a motor, an element supporting said frame and connected to one end thereof, eccentric and strap connections between the shaft of said motor and said element to vibrate the latter, equalizing means for determining the angular positions of said element during its vibrations, and a spring support for said element to take the weight thereof and of said frame from the motor shaft.

6. In a riddle the combination with a screen bearing frame of operating and supporting mechanism located wholly beyond

- one end thereof and including a motor, a hanger pendant from the motor shaft and connected to one end of said frame, eccentric and strap connections between said shaft and the hanger to vibrate the latter, equalizing springs acting on said element for determining its angular positions during its vibrations, and a spring support for said element to take the weight thereof and of said frame from the motor shaft. 75
7. In a riddle the combination with a screen bearing frame of operating and supporting mechanism located wholly beyond one end thereof and including a motor, a hanger having arms pendant from the motor shaft, the hanger being connected to one end of said frame, eccentric and strap connections between said shaft and the hanger to vibrate the latter, the arms having rearward extensions, a cross bar connecting said extensions, and equalizing springs acting on said bar at opposite sides thereof for determining the angular positions of the hanger during its vibrations. 80
8. In a riddle the combination with a screen bearing frame of operating and supporting mechanism located wholly beyond one end thereof and including a motor, a hanger having arms pendant from the motor shaft and a bridge piece connecting the arms, a centrally located stem projecting forward from the bridge piece and connected to one end of the frame, eccentric and strap connections between the motor shaft and said arms to vibrate the hanger, and a supporting spring acting on said stem to take the weight of the hanger and said frame from the motor shaft. 85
9. In a riddle the combination with a screen bearing frame of operating and supporting mechanism located wholly beyond one end thereof and including a motor, a hanger having arms pendant from the motor shaft and a bridge piece connecting the arms, a centrally located stem projecting forward from the bridge piece and connected to one end of the frame, eccentric and strap connections between the motor shaft and said arms to vibrate the hanger, a supporting spring acting on said stem to take the weight of the hanger and said frame from the motor shaft and equalizing springs acting on said hanger for determining its angular positions during its vibrations. 90
10. In a riddle the combination with a screen bearing frame of operating and supporting mechanism located wholly beyond one end thereof and including an element supporting said frame and connected to one end thereof, means arranged to hold said frame in its normal position on said element and to permit its inversion for the purpose of cleaning the screen, a motor, and means operatively connecting the shaft of 95
- the motor and said element to vibrate the latter vertically. 100
- In testimony whereof I hereby affix my signature.
